TOE CLEANING BRUSH HANDLE

Harold Safalow, 2515 Webster Ave.,
Bronx, N.Y. 10458

Filed May 5, 1969, Ser. No. 17,035

Term of patent 14 years

Int. Cl. D4—99

U.S. Cl. D4—99

FIG. 1 is a perspective view of one embodiment of the handle, the toe cleaning brush being shown in phantom lines;

FIG. 2 is a side view of the embodiment of FIG. 1; and

FIG. 3 is a side view of a modified toe cleaning brush handle.

I claim:

The ornamental design for a toe cleaning brush handle, as shown and described.
